UNITED STATES PATENT OFFICE

2,056,361

PLUGBOARD FOR TABULATING MACHINES

Albert W. Mills, Endicott, N. Y., assignor to International Business Machines Corporation, New York, N. Y., a corporation of New York

Application August 29, 1933, Serial No. 687,268

3 Claims. (Cl. 173—328)

This invention relates to perforated card controlled accounting machines and more particularly to plug boards for use in connection with such machines whereby data read from particular positions on a card may be transmitted to the desired positions in an accumulating device, or to effect control of a particular column or columns of a printing mechanism.

In machines of this type, the perforation sensing elements are usually connected to separate plug sockets on the plug board and the various denominational orders of the accumulating devices are connected to other plug sockets on the plug board. These sockets are then interconnected by inserting plugging jacks between the sockets to connect a particular card column to the desired accumulating or printing column.

In this manner various other devices such, for instance, as group control and group indicating mechanisms may also be connected to the various columns as desired.

A machine of this type is disclosed in the patent to Peirce No. 1,780,685 issued November 4, 1930. One advantage of this type of connection between the perforation sensing elements and the accumulators, columns of type, and control devices is that any column on the card may be connected to any desired accumulating column, printing column, or other device or devices. This results in an extremely flexible system in which it is possible to apply data to record cards in any desired columns and thereafter to use the cards to control the making of reports in which the data taken from the cards may be printed according to any desired arrangement on the report sheet.

With such an arrangement it is also possible to use a set of cards to control the making of a report arranged according to a given form and then to use the same set of cards to prepare a report according to an entirely different form. These various forms are obtained by rearranging the plug connections on the plug board before operating the machine.

It is frequently common practice, particularly in statistical departments, to employ certain fixed forms of report repeatedly without making any changes or with only occasional slight changes in the connections between the card columns and the printing columns.

It is one object of this invention to provide a removable plug board on which a permanent set-up may be made for a report form.

Another object is to provide a receiver for interchangeable plug boards each of which plug

boards being permanently set up for different report forms.

Another object is to provide a plug board with removable plugs and means to lock the plugs against removal when the plug board is in operative position.

Another object is to provide a plug board of the type indicated wherein clean electrical contacts between parts are assured.

Various other objects and advantages of my invention will be obvious from the following particular description of one form of mechanism embodying the invention or from an inspection of the accompanying drawings and the invention also constitutes certain new and novel features of the construction and combination of parts hereinafter set forth and claimed.

In the drawings:

Fig. 1 is a conventional wiring diagram of a tabulating machine illustrating the manner in which the invention is employed.

Fig. 2 is a view in front elevation of the plug board in position, certain parts being shown broken away for clearness.

Fig. 2a is an enlarged detail view of one of the contacts and the retaining spring therefor.

Fig. 3 is a sectional view taken on line 3—3, Fig. 2.

Fig. 4 is a fragmentary detail view illustrating the device with removable plugs and showing the method of locking the plugs against removal when the plug board is in closed position.

Fig. 5 illustrates the removable plug interconnections on the plug board.

The wiring diagram illustrated in Figure 1 is similar to the diagram shown in the above mentioned patent and is shown here more clearly to illustrate the type of machine in which the instant invention is employed. In such machines two sets of perforation sensing brushes 1 and 2 are employed. These brushes cooperate with corresponding contact members 3 and 4, one for each brush. The perforated cards are fed between the brushes 1 and 2 and their associated members 3 and 4.

When a perforation in a card column passes between a brush 1 or 2 and its corresponding member 3 or 4 the brush completes an electrical circuit through the perforation to the accumulating, printing or other control relay to effect the desired operation of the machine. Each of the numbers 3 and 4 is connected by individual wires 5 and 6 to corresponding terminals 7 and 8 on the plug board 9. Additional terminals 10 are

connected to relays 11 which control the accumulating or printing devices or both.

In order to cause a particular column on a card to control a particular accumulating order 5 or printing column, a plug connection is normally made between the respective terminals 7 and the desired terminal 10. Also when group indicating is to be effected, that is, when a group designating number is to be printed, a connection is 10 made by plugging from the desired terminal or terminals 7 to one of the terminals 17 and a similar plug connection is effected between terminals 19 and 10. With such connections the controlling circuit will extend from the positive side 15 of the line 14 to the common bar 15, individual magnet 11, terminal 10, plug connection to terminal 19, wire 20, contacts 16, terminal 17, plug connection to terminal 7, wire 6, contact member 4, brush 2 and back to the other side of the 20 line 14a.

According to the present invention these plugging connections on the plug board 9 which is made of a suitable dielectric material are omitted and a removable plug board 24 having terminals 25 10a, 7a, etc., is provided. For printing and accumulating, the connections are now made between terminals 7a and 10a as indicated by the wire 25. Now when the plate 24 is brought into cooperative relation with the plug board 9 the 30 several contacts 10a are brought into engagement with the corresponding terminal contacts 10, and contacts 7a engage 7 so that the proper connections are made between terminals 7 and 10. Similarly, for group indication, instead of 35 plugging from terminals 7 to 17 and 10 to 19 on the plug board 9, the contacts 7a and 17a, and 10a and 19a on the removable board 24 are permanently connected by wires 27 and 28. When the board 24 is brought into proper contact with 40 the board 9 the plug connections are effected between terminals 7 and 17, and 10 and 19 to carry the circuit through contacts 16.

In order to effect group control through particular columns on the cards, the selected columns 45 are connected through their brushes to magnets 21 by connecting the particular terminals 8 to the desired terminals 23. This is accomplished by connecting contacts 8a and 23a by wire 36, the contacts 8a and 23a being adapted 50 to contact terminals 8 and 23 respectively when the board 24 is attached to the board 9.

Each magnet 21 effects its control of the machine by controlling one of the sets of contacts 21a, which contacts are connected in series, each 55 set of contacts representing one column on the card. As many contacts 21a as are necessary may be used and those contacts not used may be shunted out by a connection between the terminals 37. This is effected by a wire 38 between 60 contacts 37a on the removable board 24.

When adding in a given number of denominational order totalizer wheels and the total is such as to exceed the capacity of the given number of orders, the next higher order totalizer wheel may 65 be connected to receive the overflow and to control its type element to print the total, by connecting the proper one of the magnets 11 through terminal 10 to the common terminal 39. A wire 40 may be connected between the particular contact 10a and one of the contacts 39a on the board 70 24 to effect this.

It may thus be seen that the machine may be provided with a terminal board on which all plug connections are made to contact terminals. The 75 plugging connections may be permanently made

on a removable board which, when placed on the terminal board, properly interconnect the terminals.

Referring now to Figure 3, the contacts 7a, 8a, 17a, etc., project from conductors 41 which extend through the board 24 which is made of a suitable dielectric material and to the opposite end of which conductors 41 are secured clips 42 to which may be attached the connecting wires 25, 27, 28, 36, etc. The board 24 is secured in a frame 43 which is removably supported in a hinged receiver 44 pivotally supported at 45 by projections extending downwardly and outwardly from a frame 46 in which is mounted the terminal board 9. The frame 46 may be permanently secured to the machine by brackets 47 fragments of which appear in Figure 3.

Mounted in the upwardly projecting ends of the frame 46 is a shaft 48 having a pair of latch members 49 secured thereto. A spring 50 urges 20 the shaft and the latches 49 clockwise (Fig. 3) into engagement with the removable board 24 to retain this board in cooperative relation with the terminal board 9.

When all of the connections have been made 25 between the clips 42 on the board 9 a cover plate 51 is secured to the frame 43 thus concealing and protecting the connections. Guides 52 secured to the cover plate 51 provide a convenient receptacle for a card 53 upon which may be printed or 30 otherwise marked data indicating the connections and/or form for which the particular board is wired.

In order to install the selected board 24, of 35 which there may be a plurality each wired for a different form, the latches 49 are released allowing the receiver 44 to swing outwardly, the movement of the receiver being limited by projections 54 striking stop studs 55 on the frame 46. The board 24 then in the receiver may be slid 40 upwardly and removed and the selected board may be then inserted. The receiver 44 and the inserted board 24 are then rocked counterclockwise (Fig. 3) until the latches 49 snap into position back of the frame 43. 45

As the board 24 is brought close to the board 9 the beveled ends of the contacts 7a, 8a, 17a, etc. come under the ends of the corresponding contacts 7, 8, 17, etc., camming these contacts upwardly against the tension of springs 56 50 mounted in connectors 57, thus making good electrical contacts. Projections 107 on the contacts 7, 8, 17, etc. fit within recesses 57a in the sides of the connector 57 to form pivots for the contacts and to prevent relative longitudinal movement thereof. Likewise projections 560 on the springs 56 fit in the recesses 57a on top of the contacts and in addition the right hand ends (Fig. 3) of the springs 56 are bent sharply as indicated at 56a (Figs. 2a, 3 and 4) to engage the 60 board 9 thus preventing movement of the connectors 57 in the board.

Figures 4 and 5 disclose a modified form of removable plug board in which the permanently wired connections are replaced entirely or in 65 part by detachable plug connectors. This arrangement makes possible setting up slight changes in the report form or setting up of special forms which differ widely from the former set up on the permanently wired boards.

Connectors 61 are provided with plugs 62 one 70 electrically and mechanically secured to each end thereof. The plugs 62 have channels 62a in the under side thereof and when inserted into suitable apertures in the plug board said channels are 75

pressed downwardly to engage the board by springs 63 mounted on the plugs thus insuring that the plugs may not be accidentally displaced. The cover plate 51 is omitted from this modified 5 board to accommodate the projecting ends of the plugs 62 and the connector 61.

When the receiver 44 is closed the beveled inner ends 64 of the plugs 62 cam the contacts 7, 8, 17, etc., upwardly. This action locks the plugs 62 10 against removal while the removable board is in contact with the terminal board 9.

The latches 49, in the case of the modified board, cooperate with clips 65 secured to the plug board to retain said board in cooperative relation 15 with the terminal board.

While there has been shown and described and pointed out the fundamental novel features of the invention as applied to a single modification, it will be understood that various omissions and 20 substitutions and changes in the form and details of the device illustrated and in its operation may be made by those skilled in the art without departing from the spirit of the invention. It is the intention therefore to be limited only 25 as indicated by the scope of the following claims.

What is claimed is as follows:

1. In a plugboard assembly for an electrical tabulating machine including a fixed terminal board and a movable plugboard, the combination 30 of an insertable plug having a channel engaging the movable board to prevent accidental displacement of said plug, a spring to hold the channeled plug in engagement with said board, a removable connector in the fixed terminal board 35 including, a contact member provided with retaining projections to retain said contact member in the connector, and a spring provided with retaining projections to retain said spring in the

connector, said spring having a bent portion to retain the connector in the board.

2. In a plugboard assembly for an electrical tabulating machine including a fixed terminal board and a movable plugboard, the combination 5 of a hinged receiver for the movable board, a beveled contact member in the movable board, a connector in the fixed board, said connector having recessed sides, a pivoted contact member provided with projections engaging the recessed sides 10 to retain the pivoted contact member in the connector, and a spring provided with retaining projections engaging the recessed sides of the connector to tension the contact members whereby said pivoted contact member makes a wiping connection with the beveled contact member when the movable board is brought into operative relation with the fixed board.

3. In an electrically controlled tabulating machine the combination with a plugboard assembly 20 including a fixed board and a movable board, of a connector in the fixed board, said connector having recessed sides, a contact member having projections engaging the recessed sides to retain the contact member in the connector, a spring 25 having projections engaging the recessed sides to retain the spring in the connector, said spring being adapted to tension said contact member, an insertable plug provided with a channel to engage the movable board, said plug having a 30 beveled end to make wiping contact with the contact member when the movable board is brought into operative relation with the fixed board, and a spring cooperating with the plug and with the movable board to hold the plug 35 against accidental displacement.

ALBERT W. MILLS.
